MULTIPLE PRINTING MACHINE

André Léon Victor Clément Debré, Paris, France

Application February 28, 1935, Serial No. 8,735
In France March 6, 1934

19 Claims. (Cl. 88—24)

My copending application Ser. No. 753,051 filed on November 14, 1934, describes a printing machine for the simultaneous printing of a plurality of positives from a negative passing over a cylindrical drum along the axis of which is arranged the single projecting lamp, the luminous beams issuing from the latter passing through successive images on the negative so as to impinge respectively through the superposed printing gates 5 on the positives driven by drums keyed to a common axis and arranged behind said gates. Two such machines or more may be associated for the simultaneous printing on the different positives of two or more negatives and more particularly 10 of a sound and an image negative.

My invention has for its object an improved control mechanism for a multiple machine of the last disclosed type, said mechanism including independent control means for the common frictional winding and unwinding of the different positives, for the common frictional winding and unwinding of the negatives and for the drive through an independent motor and a common control shaft of the series of superposed drums 25 providing the progress of the positives in front of their printing gates and of the negative driving drums, whereby the usual feed drums may be omitted. Moreover means are also provided for disengaging the positive films with reference to 30 their drive, which completes the independent drives provided in the machine and allows the same scene to be printed several times on one or more positives without disconnecting the positive drive with reference to the negative drive.

I will disclose my invention with reference to 35 a form of execution of a multiple printing machine provided with independent control means as specified together with certain other novel and interesting features.

In accompanying drawings:

Fig. 1 is a general perspective view of a multiple printing machine.

Figs. 2 and 3 are longitudinal cross-sections of 45 the negative driving means and of part of the casing of the apparatus respectively for the opened and closed positions thereof.

Fig. 4 shows the shaft carrying a series of positive driving drums.

Fig. 5 shows the motor ensuring the frictional drive of both negatives.

Figs. 6 and 7 are partly sectional front and plan views of one of the frictional positive winding means.

Figs. 8, 9 and 10 are sectional views of the guid-

ing channel enclosing the two successive driving drums of a positive for three different positions of the latter.

Figs. 11 and 12 are plan and side views of a system ensuring regularity of tension on the positive films in their guiding channel. 5

Fig. 13 is a detail relating to the frictional winding of a positive.

Fig. 1 shows diagrammatically the whole of the double printing machine with the omission however of the optic devices shown merely in a diagrammatic manner at L_1 and L_2 between each negative and the corresponding printing gates, said devices being preferably as described in my abovementioned copending application. In Fig. 15 1 the picture negative 1 and the sound negative 2 are unwound off their feed reels and wind on their take-up reels frictionally driven by a common motor 80. The parts played by the feed and take-up reels may be interchanged by stopping and disconnecting the motor driving the take-up reels used as feed reels and starting and reconnecting the motor 80' adapted to drive the feed reels used now as take-up reels. 20

The negative drive is performed by the drum 25 3 serving also as an apertured cylinder containing along its axis the projecting lamps. The negatives are led on to said drum by rollers mounted on stationary pivots, the elasticity of the negatives being sufficient for maintaining them in contact 30 with the driving drum. To ensure the projection of the two negatives, two lamps 16 and 17 are provided in front of the two series of gates 14—15 (Figs. 2 and 3) corresponding to pictures and sounds. The drum 3 is driven independently 35 of all the frictional drives through the general control system of the machine comprising the motor 100 secured to the base 101, the shaft thereof 99 and the connecting shaft 66 controlled thereby which carries at one end the driving pinion 40 for the drum 3. To the other end of the connecting shaft 66 is keyed a pinion 65 driving the shaft 60—60' carrying the driving drums 97—97' of the positives 5 arranged in front of the gates for printing on the latter respectively sounds 45 and pictures. An auxiliary pinion 98 is interposed between the end pinion of the shaft 66 and the shaft 60' for instance so as to make the shafts 60—60' rotate in the same direction. The positives are fed by the pile of feed reels D and are 50 wound on the pile of take-up reels R frictionally driven by the motor 96 after they have passed over the sound printing drums 97, the tension compensating rollers 125 and the picture printing drums 97'. After the plates P_1 and P_2 car- 55

55

rying each two piles of reels have rotated round their pivots as explained hereinafter with more detail, the positives wound on the reserve reels of the third pile D' (carried by plate P₁) are un-wound and rewound on the fourth pile R' (on plate P₂) which has taken the place of R and is frictionally driven by the motor 96'. The drive can be of course effected from R to D or from R' to D', if the motor 96' is set operating in place of motor 96. More generally any of the reels of one plate may be used as a feed reel with either of the reels on the other plate as a take-up reel.

The general control through the shaft 99 of the motor 100 also provides the continuous drive 15 of the light control bands 102 and 102' for sound and picture printing respectively, through the agency of the secondary shaft 103. This shaft 103 is controlled by the shaft 99 through a suitable reducing gear and carries at its ends the 20 driving drums 104—104' for the strips 102—102'.

I will now describe with greater detail the different parts of the machine.

Figs. 2 and 3 are horizontal cross-sections through the axis of the driving drum for the 25 negative picture film 1 and the negative sound film 2. This single drum or hollow shaft 3 is provided at each end with a toothwork 4—5 for driving the corresponding negative through a single row of perforations and with projecting 30 gates 14—15 in front of the location of the two negatives. The shaft or drum 3 is also provided with a part 6 cut with a toothwork adapted to be driven by the shaft 66 (Fig. 1) and has a flange 7 adapted to drive through a frictional ring 9 a 35 regulating fly wheel 8. The latter rotates in unison with a washer 11 to which it is connected by the spigot 12 and the transverse movements of the fly-wheel are damped by the springs 10 arranged between the fly-wheel and its washer. The fly-wheel 8 has for its object the absorption of the vibrations produced by the play in the gearwork and the like.

A casing 13 surrounds the drum 3 except at its front where are provided the projection slots 45 or gates 14—15. The light sources 16 and 17 arranged axially of the drum for projecting pictures and sounds are removable. The cover 18 of the casing allows their speedy dismantling. The cooling is effected by a circulation of air 50 from the pipes 19—19' passing through the casing; this air after it has passed round the lamps 16—17 escapes through the apertures 20—20' in front of which the flange of the cover 21 forms a light-tight joint.

55 The general casing of the machine may be opened by means of the doors 22—22' and it is necessary to shut off the light from the sources 16—17 when these doors are open so as not to allow any intense illumination of the printing room. To this end I use a cylindrical sliding shutter 23 with two apertures 24—24' protected by glass panes ensuring the rigidity of the films in spite of the pressure of the air inside the shutter, said apertures corresponding normally with 60 the projection gates 14—15. The shutter 23 which is locked against rotation by a spigot 25 is connected through a projection 25 with the system for locking the doors 22—22'. The projection 25 is engaged in the forked end of a lever 28 carried by a spindle 29, the other end of which carried an arm 30. A spiral spring 31 urges this arm into contact with a double lever 32 pivotally secured at 33 to the door 22. When the doors 22—22' are closed (Fig. 2), the shutter 23 does 70 not come into the way of the projection operation

but as soon as they open (Fig. 3) the shutter 23 closes the slots 14 and 15 as explained herein-after.

The door-locking system which controls the sliding movements of the shutter 23 comprises 5 a spindle 34 controlled by the knob 35 and rotatably carried by the guiding bearing 36 secured to the door 22. A cam 37 keyed to the spindle 34 has a helical groove 38 engaged by the end of the double lever 32. The square 39 forming the 10 end of the spindle 34 engages a sleeve 40 carrying a bolting projection 41. A spring 42 is arranged round the sleeve 40 between said projection 41 and a projection 44 on the door 22, in which latter projection the sleeve may slide. A spigot 43 15 is on the sleeve abutting against projection 44 prevents said sleeve from moving outwardly towards the door 22' and enters the recess 45 in the projection 44 when the sleeve has rotated through 180° away from the position shown in 20 Fig. 2. The doors being closed, the bolting projection 41 is held in a jaw 46 of the door 22'. In order to allow a control of the bolting from the side of door 22', the latter is provided with the same control means as the door 22 including 25 chiefly a sleeve 47 carried by a spindle 34' and adapted to engage the sleeve 40 through the catches 48 whereby the knob 35' is adapted to control the rotation of the bolting projection 41. Moreover an insulating plate 49 drivingly connected with the cam 37 carries a contact strip 50 adapted to close, over a blade 51 secured to the insulating plate 52 on the door 22, the circuit of a signalling lamp, not shown, as soon as 30 the doors are locked in their closed position. 35

The working of the locking system is as follows: when the doors are to be opened, the operator turns the knob 35; the cam 37 rotates then whereby it shifts the double lever 32 the movement of which is accompanied by the arm 30 urged by its spring 30, which brings the shutter 23 in front of the projection slots 14 and 15 so as to close the latter. At the same time the bolting projection 41 rotates and passes out of the jaw 46 whereby it allows the opening of the doors 22—22'. Moreover the spigot 43 which has entered the recess 45 is held therein by reason of the pressure of the spring 42 and consequently the sleeve 40 is held in place and so is the lever 32 whereby the sliding shutter 23 can no longer move and the sliding shutter 23 is locked against displacement. When it is desired to dismantle said shutter, for instance with a view to cleaning the glass panes, a releasable stop 54 allows the lever 28 to be held away from the projection 55 25 on the shutter.

On the other hand, there are provided for controlling the illumination of the printing lamps 16 and 17 photo-electric cells 55—56 carried by the casing 13 for receiving part of the illumination 60 from the lamps through the slots 57—58 in the shutter 23 registering with cooperating slots in the drum 3. This allows a supervision of the intensity of the lights emitted at any moment by means of galvanometers, not shown, electrically 65 connected with these cells.

Fig. 4 is a cross-section along the longitudinal axis of one of the vertical shafts carrying the driving drums of the positive films, said films being adapted to receive on said drums the parallel projecting beams from the optic system in front of the corresponding negative.

The shaft 60 illustrated is controlled by the pinion 61 meshing with the pinion 65 keyed to the end of the shaft 66. This pinion 61 is yieldingly 75

- mounted on the shaft 60 and is provided to this effect with a recess 62 filled with rubber or the like yielding material. The driving teeth 63 secured to the hub 64 keyed to the shaft 60 and passing through this yielding material transmit the rotation of the pinion 64 to the shaft 60 without transmitting any vibrations from the pinions 61 and 65. A stop ring 67 holds the pinion 61 in contact with the hub 64.
- 10 The shaft 60 is rotatably held in the bearings 68 and 69 and carries different drums 70-70' provided with the toothworks 71-71' driving the positive through a single row of perforations. These drums are arranged just above the yielding secured pinion 61. To the lower end of the shaft 60, a flanged hub 72 is rigidly secured; said hub is adapted to receive a fly-wheel 73 frictionally driven by the friction wheel 74. Compensating springs such as 75 bear against the washer 76 which rotates together with the fly-wheel under the action of the spigot 77. The casing 78 contains the different parts 61 to 68 and 72 to 77 and a projection 79 on the general frame of the machine serves to carry the upper bearing 69.
- 15 Fig. 5 shows one of the two frictional drives used in alternation for taking up the negatives as stated hereinabove. This drive comprises a motor 80 secured to the support 81 and the shaft of which projects on either side for frictionally driving the corresponding negatives. This motor carries on each elementary shaft such as 82 a key 83 for securing the hub 84. A nut 85 holds this hub in place, which hub carries the frictional ring 86 driving through adherence the sleeve 87 provided with a flange 88. The sleeve 87 is 20 provided at its periphery with grooves 89 ensuring the drive of the hub of the take-up reel of the negative considered.
- 25 For keeping the sleeve 87 longitudinally in place I use an easily removable stop system comprising a plug 90 held in place by balls 91 engaging an annular groove on the hub and submitted to the action of springs 92 compressed by screws 93. A friction ring 94 is interposed between the plug 90 and the hub 84.
- 30 The driving system 80', as shown, serves exclusively for the frictional unwinding of the two negatives, with their two sleeves 87' rotating over their hub 84', stationary at the moment considered, against the frictional resistance of the ring 86'. When the unwinding is performed in the opposed direction, the motor 80' is started for frictionally rewinding the negatives whereas the motor 80 being stopped, the unwinding is performed against the action of friction off the sleeves 87 carried by the shaft ends 82. The elements controlled by 80' such as 84', 87', 86' being exactly similar to the corresponding elements 84, 87, 86 are not shown.
- 35 Figs. 6 and 7 are a sectional side view and a plan view of one of the double friction drives for positives comprising a plate P₁ and two piles of reels D and D'. The motor 96 is secured inside a casing 105 to the frame A of the machine. A plug 204 allows removal of the motor. The motor shaft is provided at its upper end with a small pinion 111 and at its lower end with a ratchet wheel 206 the part played by which is described hereinafter.
- 40 The pivoting plate P₁ encloses a gearwork under the cover 208. This plate is adapted to rotate round the casing 105, over a securing ring 209. However the rotation of the plate is eccentric with reference to the pinion 111 of the motor 96. The plate P₁ carries two intermediary pinions 108-108' the position of which is such that one of them meshes with the pinion 111 on the motor shaft while the other is spaced with reference thereto. These pinions are in permanent mesh with the large diameter pinions 200-200' which carry the elongated hubs 109-109' for the piles of reels D and D'. A key 213 is laid in a longitudinal groove of each hub 109-109'.
- 45 For increasing the rigidity of the hub, a vertical spindle 214 passes through the plate and hub and ends with a ring 215 held over the top of the hub with bearings 216-217 of material having a very low coefficient of friction and requiring no lubrication interposed between the hub and the spindle.
- 50 The hub removably carries friction plates 218 and the film-carrier plates 219, the former of which are secured to the hub 109 through the key 213. The film-carrier plates 219 are frictionally driven by the plates through the interposed friction rings 220. A nut 221 holds the plates 219-218 in place but of course, without locking them together and the film reel 222 is wound in the usual manner over the carrier plate 219. I may thus superpose round each hub 109-109' a number of friction plates, each provided with an independent friction plate forming with it a removable unit, the friction plate and the corresponding carrier plate being permanently coupled together.
- 55 As stated the printing machine comprises a double system P₁ P₂ of two reels to either side of the printing shafts 60, 60'. The positives may be wound say from P₁ on to P₂ for a first series of copies and the next set may be wound from P₂ on to P₁ for a second series of copies. When the reels on plates 219 are feed reels, the motor 96 is at a standstill as the traction on the film is ensured by the driving drums such as 97. However it is of interest to lock the hub 109 so that the film may be rigid as it passes off the reel towards the printing drums.
- 60 This is obtained, the gearwork 111-200 remaining in mesh, by the sprocket wheel 206 on the motor shaft which is prevented by a catch 45 from rotating independently of the motor in the direction corresponding to the direction of the traction exerted by the unwinding film. The hub 109 being thus held stationary by the motor, the positive reels 222 unwind tautly against the 50 friction exerted by the friction plates 218-220.
- 65 When the first series of copies is made, the operator causes the plate P₁ to rotate so as to reengage pinion 108' previously disengaged whereby the pile of reels D' may form the take-up reels. As soon as the positive films have begun winding round hub 109' and the motor 96 has been started, the different reels driven by the friction plates 218-220 continue winding. For this direction of winding, the free wheel 206 60 does not interfere with the connection of the motor 96.
- 70 For the printing of successive series of positives and for each plate P₁ P₂ the motor is in alternation operative in a given direction for 65 winding the films on their take-up reels or locked with a frictional brake impressed on the unwinding of the films.
- 75 I may provide non-actinic witness lamps at the upper part of the machine frame for allowing supervision of the operation of the motors 96 and the like.
- 80 It will be noted that the pile of reels D' temporarily out of mesh with reference to the motor 96 is adapted to receive a reserve pile, rap- 75

idly set in place, of unimpressed positives which are submitted to printing in the above described manner after a half revolution of the plate P_1 (or P_2) carrying it. It is of interest to lock the 5 spindle $109'$ of the reserve pile against rotation in order to prevent an untimely unwinding of the reserve films before use. This locking is provided through the pivotal motion of the plate P_1 which causes the pinion 111 on the motor-shaft to mesh with the intermediary wheel 108 controlling the friction drive of the other pile D . To this end, the casing 105 of the motor 96 is provided at its upper end with a toothwork 106 the axis of which is eccentric with reference to 10 the pair of secondary pinions $107-107'$ carried by the shafts of the intermediary wheels $108-108'$. According to the angular position given to the plate P_1 carrying the two piles of 15 reels, one or the other of the secondary pinions 107 or $107'$ (for the position shown) meshes with the stationary toothwork 106 . Thus the pile toothwork meshing with 106 and which is 20 obviously the one which is not in mesh with the motor-controlled pinion 111 is held against rotation. When the plate P_1 is revolved through 25 180° , the secondary pinion $107'$ ceases, with a slight pivotal motion round its own axis, being in mesh with the stationary toothwork 106 while the pinion $108'$ engages the pinion 111 so as to 30 allow the unwinding of the reserve reels D' , the motor 96 remaining stationary during this unwinding by reason of the presence of the free wheel 206 interposed between the motor and 111 or else the motor may be caused to rotate in the 35 direction required for tensioning the film during unwinding or for furthering said unwinding. At the same time the secondary pinion 107 is locked in its turn to prevent unwinding of any further reserve reels carried by hub 109 .

40 Returning to the arrangement of the friction drive of the reel carrier plates 219 , it should be noted that this arrangement prevents any undesirable loop from forming between the printing drum and the take-up reel, by reason of the tension of the film being effected automatically without any jerk; as soon as the motor 96 is set in operation the film is tensioned and when the motor 100 is started in its turn the tensioned film remains taut by reason of the resistance afforded 45 by the friction. Fig. 13 is a detail view of a modification of the friction drive for one or more films to be wound or unwound in the machine. In this figure somewhat similar to Fig. 6 261 is a spindle carrying a pulley 262 and rotatably mounted in the bearing 263 . A plate 264 keyed to the spindle 261 is provided with a friction ring 265 . Said ring is in contact with a plate 266 the diameter of which is sufficient for carrying the desired film length. The plate is provided with a hub 267 round which the film 268 is wound. The spindle 261 ends as a part 269 serving solely as a centering for the plate 266 . The rotation of the spindle 261 controlled mechanically, is thus frictionally transmitted as in the case of Fig. 6 to the film carrying plate 266 . The pressure on the friction ring 265 depends on the weight of the film and is thus proportional to the torque to be exerted for winding or unwinding.

70 In a general manner the frictional drive for the take-up reels of the negatives and positives should be such that the tension of the film on the feed side is greater than on the take-up side. To this end, I may advantageously make the feed reel friction spindles rotate in a direction op-

posed to the unwinding whereby the difference between the speeds of the friction drives on the feed and take-up sides is always greater than the absolute speed of the take-up friction drive.

Figs. 8 to 12 show the channel guiding a positive in front of its printing drums and relate to an improved manner of feeding the film into said channel. Heretofore films were inserted in front of the gates of the machine sidewise, generally after opening part of the passage. As 10 illustrated, the incurved shape and the breadth of the passage or channel passing round one or both driving sprockets or drums constrains the film, simply loaded or engaged through one end to follow under the action of its elasticity the 15 smooth wall of the channel opposed to the sprocket teeth and to pass out through the other end of the passage. The meshing with the driving sprocket or drum for operation in either direction is provided through a traction on the ends of 20 the film inserted in the channel while any subsequent desired disengagement of the film may be simply obtained by giving it slack.

The passage illustrated in Figs. 8 to 10 comprises two parts 120 passing at 121 through a half-circle round the corresponding driving drums 122 (which are those referred to as $97, 97'$ on Fig. 1) at a small distance thereof. Between these two parts the concavity of which is directed along parallel lines is arranged a U-shaped part 126 30 of opposite concavity surrounding at $121'$ the compensating roller 125 at a small distance thereof. Two small plates 123 secured to the frame A of which parts 120 form an extension arrive tangentially against the roller 125 . Lastly beyond 35 the drums and in front of the outer ends of the parts 120 ending each with a roller 128 , are arranged uprights 127 forming part of the general frame A .

The films moving in either direction in the 40 channel bounded on one side by the elements $128-120-123-125-123-120-128$ and on the other by the elements $127-122-126-122-127$ receive the impressions of sounds and pictures through the gates $129-129'$ provided in the 45 parts 120 .

The setting of the film in place is performed 50 simply by pushing it into either end of the above-defined channel. The film moves forwards under the action of its elasticity in contact with the concave portions of parts 120 and 126 between which parts it passes across the channel (see Fig. 8 illustrating the loading of the film). Thus the film is prevented from any contact with the sprocket teeth from which it is spaced through 55 part of the width of the channel.

The engagement of the film with the sprocket teeth through perforations on one side only or on both sides of said film is performed automatically as shown in Fig. 9 by drawing out the ends 60 of the film. Such a traction may be exerted by causing the rotation in the desired direction of friction rollers $130-130'$ over which the film passes on either side of the channel.

A particularly advantageous application of this arrangement is that of repeated and successive 65 printings of the same scene on the positive. I avoid thus any disconnection between the driving drums of the negatives and of the positives which are positively driven as described hereinabove by common control means. It is sufficient to slacken the ends $131-132$ of the positive film (Fig. 10) for instance by unwinding slightly the friction drives. Thus the film disengages the drum toothwork and comes under the action of 70 75

its elasticity against the concave parts of the channel. This disengages temporarily the positive with reference to the drums and allows the negatives to be unwound or rewound during this 5 time, together if required with the light control strips such as 102—102' or the like, without the positive continuing to be driven. I may thus after a first printing on the positives, rewind the negatives without moving the positives considered 10 so that it becomes possible to make a second impression following a first impression and identical therewith and so on.

The parts 120 also form doors for opening the corresponding ends of the passage, said doors being 15 preferably mounted on the pivots 133 of the rollers 128. The gates being opened, it is possible to have access to the inside of the channel for its upkeep.

A film air-cleaning means is constituted by a 20 system of ducts provided in these doors and the opposite uprights 127—127'. To this end air is blown in at the entrance and outlet of the channel through ducts 134—135, the air passing out of the 25 channel through the symmetrical ducts 134'—135'. A contact c may be provided for signalling when the doors are closed.

I have shown in Figs. 11 and 12 how the superposed compensating rollers 125 are mounted so as to move yieldingly in the direction XY of Fig. 30 10 for ensuring uniformity in the tension of the corresponding film between its two driving sprockets.

The pivot 136 of the compensating roller 25 is held (Fig. 12) between the levers 137—138 of 35 which one, 137, is notched. These levers which provide compensation for the film tension rotate respectively round pivots 139—140 carried by a stationary strap 141. On the other hand the rear ends of the levers are connected through a 40 return spring 142 urging the roller 125 to move in the direction of the arrow K of Fig. 12 so as to provide a uniform tension for the film 143 as it passes round the roller. A spigot 144 carried by the lever 138 and engaging a slot in the strap 141 45 determines the ends of the path allowed for the roller 125. Lastly an amplifying hand 145 preferably with an illuminated pointer shows the amount of tension of the film by following the to and fro motions of the roller 125. This hand is 50 carried by a spindle 147 mounted on the strap 141 and is connected with the lever 138 through its projection 148 engaging an aperture in the latter. A protecting ring 149 surrounds the parts above roller 125 controlling the position of same.

55 Fig. 11 shows a common support 150 carrying the superposed straps 141 housing in their turn the springs 142 in a transversal recess. Two parallel horizontal rods 151—152 are secured in bearings 153—154 carried by the frame A. A 60 stop system comprising a ball 155 submitted to the action of a spring 156 compressed by a set screw presses, through a slot in the bearing 153, on the rod 152 at any chosen point of its length, whereby it is possible to place correctly and at 65 will the unit constituted by the rollers 125 and their compensating means with reference to the frame A and consequently to give the proper length to the film loop between the picture printing gate and the sound printing gate.

70 What I claim is:

1. A multiple projection printing machine for printing a plurality of negative impressions simultaneously on a plurality of positives, comprising a hollow printing drum provided with longitudinally spaced peripheral series of apertures,

toothworks adapted to engage the negatives and to drive them past the printing drum, illuminating means arranged inside the hollow drum and adapted to project beams of light through the apertures in the drum, a set of parallel shafts, 5 sprocket wheels keyed thereto and adapted to engage the positives, optic means adapted to lead the beams of light passing out of the apertures towards the sprocket wheels on the shaft corresponding to series to which the aperture considered belongs a common positive control for the two shafts adapted to drive the toothworks and friction drives independent of one another and independent of the said common control adapted to take up and to feed the negatives on one hand 10 and the positives on the other.

2. A multiple projection printing machine for printing a plurality of negative impressions simultaneously on a plurality of positives comprising a frame, a common rotary hollow printing 20 drum, provided with longitudinally spaced series of apertures, toothworks carried by said drum and adapted to positively drive the negatives past the printing drum, illuminating means arranged inside the hollow drum and adapted to project 25 beams of light through the apertures in the drum, a set of parallel shafts, sprocket wheels keyed thereto and adapted to positively drive the positives, optic means adapted to lead the beams of light passing out of the apertures towards the 30 sprocket wheels on the shaft corresponding to the series to which the aperture considered belongs, a common positive control for the two shafts adapted to drive the hollow drum and friction drives independent of one another and independent of the said common control adapted to take up and to feed the negative on one hand and 35 the positives on the other.

3. A multiple projection printing machine for printing a plurality of negative impressions simultaneously on a plurality of positives, comprising a common rotary hollow printing drum, provided with longitudinally spaced series of apertures, toothworks carried by the drum adapted to drive the negatives past the printing drum, 45 illuminating means arranged inside the hollow drum and adapted to project beams of light through the apertures in the drum, a fly wheel frictionally driven by the rotary drum, a cold-air circuit for the illuminating means, photoelectric 50 means adapted to control the intensity given out by the illuminating means, a set of parallel shafts, sprocket wheels keyed thereto adapted to positively drive the positives, optic means adapted to lead the beams of light passing out of the apertures towards the sprocket wheels on the shaft corresponding to the series to which the aperture considered belongs, a common positive control for the two shafts adapted to drive the hollow 55 drum and friction drives independent of one another and independent of the said common control adapted to take up and to feed the negatives on one hand and the positives on the other.

4. A multiple projection printing machine for printing a plurality of negative impressions simultaneously on a plurality of positives, comprising a casing, doors for said casing, locking means for the casing doors, a common rotary hollow printing drum, provided with longitudinally spaced series of apertures inside the casing, toothworks 70 carried by the drum adapted to drive the negatives past the printing drum, illuminating means arranged inside the hollow drum and adapted to project beams of light through the apertures in the drum, a cylindrical shutter slidingly 75

- mounted on the drum, means whereby operativeness of the door locking means causes the shutter to obscure the apertures in the drum, a set of parallel shafts, sprocket wheels keyed thereto 5 adapted to positively drive the positives, optic means adapted to lead the beams of light passing out of the apertures towards the sprocket wheels on the shaft corresponding to the series to which the aperture considered belongs, a common positive 10 control for the two shafts adapted to control the hollow drum and friction drives independent of one another and independent of the said common control adapted to take up and to feed the negatives on one hand and the positives 15 on the other.
5. A multiple projection printing machine for printing a plurality of negative impressions simultaneously on a plurality of positives, comprising a hollow printing drum provided with longitudinally spaced series of apertures, toothworks adapted to drive the negatives past the printing drum, illuminating means arranged inside the hollow drum and adapted to project beams of light through the apertures in the drum, a set of parallel shafts, sprocket wheels keyed thereto adapted to drive the positives, optic means adapted to lead the beam of light passing out of the apertures towards the sprocket wheels on the shaft corresponding to the series 20 to which the aperture considered belongs, a motor, a common shaft driven by the motor, gearworks connecting said common shaft with both parallel shafts on one hand and the toothworks on the other, light controlling strips controlled by the said common shaft and adapted to provide respectively the changes in light intensity required by the corresponding negatives and friction drives 25 independent of one another and independent of the said common motor and shaft arrangement adapted to take up the negatives on one hand and the positives on the other.
8. A multiple projection printing machine for printing a plurality of negatives simultaneously on a plurality of positives comprising a common rotary hollow printing drum provided with longitudinally spaced series of apertures, toothworks carried by the drum and adapted to drive the different negatives past the printing drum, illuminating means arranged inside the hollow drum and adapted to project beams of light through the apertures in the drum, a set of parallel shafts, sprocket wheels keyed thereto adapted to drive the positives, optic means adapted to lead the beams of light passing out of the apertures towards the sprocket wheels on the shaft corresponding to the series to which the aperture considered belongs, a common positive control for the two shafts and for the hollow drum, a friction drive independent of said common control adapted to take up the positives, a motor independent of the said positive control and friction drive and friction drives adapted to take up the corresponding negatives controlled by last mentioned motor on either side thereof.
9. A multiple projection printing machine for printing a plurality of negative impressions simultaneously on a plurality of positives comprising a common rotary hollow printing drum provided with longitudinally spaced series of apertures, toothworks carried by the drum and adapted to drive the negatives past the printing drum, illuminating means arranged inside the hollow drum and adapted to project beams of light through the apertures in the drum, a set of parallel shafts, sprocket wheels keyed thereto adapted to drive the positives, optic means adapted to lead the beams of light passing out of the apertures towards the sprocket wheels on the shaft corresponding to the series to which the aperture considered belongs, a common positive control for the two shafts and for the hollow drum, two friction drives including each a motor independent of said common control, a pile of superposed coaxial rotary plates controlled thereby and positive reel carriers lying on each plate in frictional cooperation therewith and a friction drive independent of said common control and two last mentioned friction drives adapted to take up the negatives.
10. A multiple projection printing machine for printing a plurality of negative impressions simultaneously on a plurality of positives comprising a common rotary hollow printing drum provided with longitudinally spaced series of apertures, toothworks carried by the drum and adapted to drive the negatives past the printing drum, illuminating means arranged inside the hollow drum and adapted to project beams of light through the apertures in the drum, a set of parallel shafts, sprocket wheels keyed thereto adapted to drive the positives, optic means adapted to lead the beams of light passing out of

the apertures towards the sprocket wheels on the shaft corresponding to the series to which the aperture considered belongs, a common positive control for the two shafts and for the hollow drum, two friction drives including each a motor independent of said common control, the motorshaft thereof, a support eccentrically rotatable round the axis of rotation of the motorshaft, two piles of superposed coaxial rotary plates carried by the support, a gearwork controlling each of them and adapted to be operatively driven by the motor in alternation according to the angular position occupied by the rotatable support, and the positive reel carriers lying on each plate in frictional cooperation therewith and a friction drive independent of said common control and two lastmentioned friction drives adapted to take up the negatives.

11. A multiple projection printing machine for printing a plurality of negative impressions simultaneously on a plurality of positives comprising a common rotary hollow printing drum provided with longitudinally spaced series of apertures, toothworks carried by the drum and adapted to drive the negatives past the printing drum, illuminating means arranged inside the hollow drum and adapted to project beams of light through the apertures in the drum, a set of parallel shafts, sprocket wheels keyed thereto adapted to drive the positives, optic means adapted to lead the beams of light passing out of the apertures towards the sprocket wheels on the shaft corresponding to the series to which the aperture considered belongs, a common positive control for the two shafts and for the hollow drum, two friction drives including each a motor independent of said common control, a pile of superposed coaxial rotary plates controlled thereby, positive reel carriers lying on each plate in frictional cooperation therewith and a free wheel carried by the motorshaft for preventing its rotation in the direction corresponding to the unwinding of the positives, and a friction drive independent of said common control and two last mentioned friction drives adapted to take up the negatives.

12. A multiple projection printing machine for printing a plurality of negative impressions simultaneously on a plurality of positives comprising a common rotary hollow printing drum provided with longitudinally spaced series of apertures, toothworks carried by the drum and adapted to drive the negatives past the said drum, illuminating means arranged inside the hollow drum and adapted to project beams of light through the apertures in the drum, a set of parallel shafts, sprocket wheels keyed thereto adapted to drive the positives, optic means adapted to lead the beams of light passing out of the apertures towards the sprocket wheels on the shaft corresponding to the series to which the aperture considered belongs, a common positive control for the two shafts and for the hollow drum, two friction drives including each a motor independent of said common control, a pile of superposed coaxial rotary plates controlled thereby and positive reel carriers lying on each plate in frictional cooperation therewith and forming a removable unit with the said underlying plate and a friction drive independent of said common control and two last mentioned friction drives adapted to take up the negatives.

13. A multiple projection printing machine for printing a plurality of negative impressions simultaneously on a plurality of positives comprising

a common rotary hollow printing drum provided with longitudinally spaced series of apertures, toothworks carried by the drum adapted to drive the negatives past said drum, illuminating means arranged inside the hollow drum and adapted to project beams of light through the apertures in the drum, a set of parallel shafts, sprocket wheels keyed thereto adapted to drive the positives, optic means adapted to lead the beams of light passing out of the apertures towards the sprocket wheels on the shaft corresponding to the series to which the aperture considered belongs, a common positive control for the two shafts and for the hollow drum, two friction drives including each a motor independent of said common control, the motorshaft thereof, a support eccentrically rotatable round the axis of rotation of the motorshaft, two piles of superposed coaxial rotary plates carried by the support, a gearwork controlling each of them and adapted to be operatively driven by the motor in alternation according to the angular position occupied by the rotatable support, carriers for the positive reels lying on each plate in frictional cooperation therewith and a stationary toothwork adapted to engage the gearwork of the pile which is not operatively connected with the motor and a friction drive independent of said common control adapted to take up the negatives.

14. In a machine as claimed in claim 2 a passageway for each positive film in front of its sprocket wheels, said passageway passing over a half circumference round the sprocket wheel and adapted to constrain the film urged into one end of the passageway to follow under the action of its elasticity the wall opposed to the wheel.

15. In a machine as claimed in claim 2 a passageway for each positive film in front of its sprocket wheels, said passageway passing over a half circumference round each sprocket wheel with a concavity directed in the same direction for the different wheels, said cavities being connected through a concavity of opposite direction merging tangentially into the first concavities, a roller between the successive sprocket wheels arranged in said oppositely directed concavity of the passageway, the passageway being adapted to constrain the film urged into one end thereof to follow under the action of its elasticity the wall portions opposed to the wheels and to the roller respectively.

16. In a machine as claimed in claim 2 a passageway for each positive film in front of its sprocket wheels, said passageway passing over a half circumference round each sprocket wheel with a concavity directed in the same direction for the different wheels, said concavities being connected through a concavity of opposite direction merging tangentially into the first concavities, a roller between the successive sprocket wheels arranged in said oppositely directed concavity of the passageway, a yielding support for the roller for uniformizing the tension of the film, the passageway being adapted to constrain the film urged into one end thereof to follow under the action of its elasticity the wall portions opposed to the wheels and to the roller respectively.

17. In a machine as claimed in claim 2 a passageway for each positive film in front of its sprocket wheels, said passageway passing over a half circumference round each sprocket wheel with a concavity directed in the same direction for the different wheels, said concavities being connected through a concavity of opposite direc-

tion merging tangentially into the first concavities, a roller between the successive sprocket wheels arranged in said oppositely directed concavity of the passageway, the passageway being adapted to constrain the film urged into one end thereof to follow under the action of its elasticity the wall portions opposed to the wheels and to the roller respectively, the passageway including parts adapted to be opened for allowing 10 access inside same.

18. In a machine as claimed in claim 2 a passageway for each positive film in front of its sprocket wheels, said passageway passing over a half circumference round each sprocket wheel 15 with a concavity directed in the same direction for the different wheels, said concavities being connected through a concavity of opposite direction merging tangentially into the first concavities, a roller between the successive sprocket 20 wheels arranged in said oppositely directed concavity of the passageway, the passageway being adapted to constrain the film urged into one end thereof to follow under the action of its elasticity the wall portions opposed to the wheels and to

the roller respectively, the passageway including air circulating means for cleaning same.

19. In a machine as claimed in claim 2 a passageway for each positive film in front of its sprocket wheels, said passageway passing over a half circumference round each sprocket wheel 5 with a concavity directed in the same direction for the different wheels, said concavities being connected through a concavity of opposite direction merging tangentially into the first concavities, a roller between the successive sprocket wheels arranged in said oppositely directed concavity of the passageway, a yielding support for the roller for uniformizing the tension of the film, the passageway being adapted to constrain 10 the film urged into one end thereof to follow under the action of its elasticity the wall portions opposed to the wheels and to the roller respectively and a common holder for the yielding supports of the rollers adapted to be adjustably secured to the machine frame. 15 20

ANDRÉ LÉON VICTOR CLÉMENT DEBRIE.
